UNITED STATES PATENT OFFICE.

EDWARD J. POWERS, OF OAK PARK, ILLINOIS.

SAFETY MECHANISM FOR HOISTING APPARATUS.

Application filed April 20, 1925. Serial No. 24,382.

To all whom it may concern:

Be it known that I, EDWARD J. POWERS, a citizen of the United States of America, residing at Oak Park, in the county of Cook and State of Illinois, have invented certain new and useful Improvements in Safety Mechanism for Hoisting Apparatus, of which the following is a specification.

This invention relates to automatic catch mechanisms and the like, whereby the rotation of the primary pinion of the gearing of the mechanism, other than by the driving shaft, is prevented, when from any accidental cause said driving shaft fails to function as a driver, and the present improvement has for its object:

To provide a structural formation and association of parts in which the primary pinion or like member of the gearing of a hoisting or like mechanism, is caught and held from rotation in either direction, when from any accidental cause the driving or power shaft carrying said pinion fails to function. The construction involving a relative formation of parts wherein the driving or power shaft has a limited independent turning movement in relation to the aforesaid pinion, with said pinion carrying a pair of reversely arranged ratchet pawls or dogs for alternating engagement with a circular ratchet formation on a portion of the stationary supporting frame of the apparatus, to catch and hold said pinion against rotation except when the said pinion is positively driven by said power shaft, all as will hereinafter more fully appear.

In the accompanying drawings:

Fig. 1, is a longitudinal sectional elevation of the primary pinion of the gearing of a hoisting machine in associated relation to the power shaft and fixed bearing for an end of the shaft, and having the present improvement applied.

Fig. 2, is a detail longitudinal section on line 2—2, Fig. 4, of one of the ratchet pawls, its operating cam studs and accessories.

Fig. 3, is a similar section on line 3—3, Fig. 4, of the companion ratchet pawl of the mechanism.

Fig. 4, is a transverse sectional elevation on line 4—4, Fig. 1, with the stationary parts of the mechanism omitted, and showing the ratchet pawls held in a retracted and inactive position and with the power shaft in direct operative engagement with

the pinion for driving the same in the contra-clockwise direction indicated by an arrow on said figure.

Fig. 5, is a companion view to Fig. 4, showing the position of the parts, with one of the ratchet pawls released when the pinion turns in a clockwise direction in advance of the power shaft through accidental stoppage or failure of the motive power connection of said shaft.

Fig. 6, is a companion view to Fig. 5, showing the position of the parts with the other of the ratchet pawls released, when the aforesaid pinion turns in a contra-clockwise direction in advance of the power shaft, through the causes mentioned in connection with Fig. 5.

Fig. 7, is a companion view to Fig. 4, showing the ratchet pawls in a retracted and inactive position when the power shaft is in direct operative engagement with the aforesaid pinion and moving said pinion in a clockwise direction as indicated by an arrow on the figure.

Fig. 8, is a detail sectional elevation of the ratchet disk, normally stationary with the fixed frame or support of the mechanism.

Fig. 9, is a detail perspective view of a ratchet pawl and its operating cam stud on the power shaft, the parts being shown in separated relation.

Like reference numerals indicate like parts in the several views.

In the present safety mechanism, the primary or driving pinion 1 of a hoisting or like mechanism is connected to the power shaft 2 upon which said pinion is carried, by a spline or key 3 having limited independent turning movement in a keyway 4 of the elongated form shown, so that limited independent turning movement between the pinion and power shaft is provided for the purpose hereinafter set forth.

The end of the power shaft 2 carrying the pinion 1, is journaled in a fixed bearing box 5 on the frame or housing of the mechanism, and associated with said bearing box 5, or like stationary part of the frame, is ratchet disk 6, the circularly arranged ratchet recesses 7 of which are in adjacent relation to an end of the pinion 1 aforesaid.

The ratchet disk 6 may form a fixed part of the bearing box 5 or other fixed part of the carrying frame of the mechanism, in the preferred construction however, the

ratchet disk 6 is frictionally attached to said box or frame, so as to be capable of independent movement under a sudden and forcible stress, and thus avoid breakage of parts which is liable to occur, when the ratchet pawls hereinafter described have sudden engagement with said ratchet disk under a heavy load carried by a hoisting or like machine. The frictional engagement of the ratchet disk 6 and a fixed part of the supporting frame, such as the bearing box 5, is preferably attained by the arrangement of a flat marginal portion 6' of the ratchet disk between a complementary disk or head 8, fixedly connected to the bearing box 5, and an annular ring 8', with said head 8 and ring 8' held in adjustable frictional contact with the marginal portion 6' of the ratchet disk by a plurality of clamping bolts 9, and with the bearing faces of said head and said ring preferably provided with annular inserts 10 of any usual material used in the present art to afford constant friction during extended use.

25 In the present structure, the circularly arranged series of holding recesses 7 in the ratchet disk 6, are preferably in the forms of truncated sectors, as shown, to afford stop abutment at the respective sides of each recess for the reversely arranged ratchet pawls now to be described.

A pair of ratchet pawls 11 and 12, are movably mounted in the primary pinion 1 aforesaid, and preferably in a slideable manner in longitudinal recesses in said pinion, in which they have movement in a direction towards the ratchet disk 6 through springs 13 as shown in Fig. 1. The ratchet pawls 11, 12, with their holding recesses are located 40 at opposite sides of the axis of rotation of the pinion 1, with the forward and beveled end of the pawl 11 adapted for stop engagement with the ratchet disk 6 when the pinion is turning in one direction, while the forward and beveled end of the companion pawl 11 is adapted for stop engagement with the ratchet disk 6 when the pinion 1 is turning in a direction opposite to that above referred to.

50 When the pawls 11, 12 are of a cylindrical shape, as shown in Fig. 1, they will carry splines or keys 14 moving in keyways in the pinion 1 to prevent turning of the pawls from their proper position.

55 In the present improvement it is required that the pawl 11 or pawl 12 which would normally act to hold the pinion 1 from rotation in the desired direction, be held in a retracted and inactive position during a normal rotation of the pinion 1 and power shaft 2 in the desired direction, and to such end each pawl 11, 12 is formed with an inclined or cam face 15, 15' facing in the same direction as shown in Figs. 1, 2 and 3, with 60 said cam faces adapted to be alternately and

operatively engaged by cam studs or projections 16, 16' on opposite sides of the power shaft 2, so that with a cam stud 16 in operative engagement with the cam face 15 of a ratchet pawl 11 to hold the same in a retracted position, the other cam stud 16' will be out of engagement with the cam face 15' of the pawl 12, to permit the same to move into stop engagement with the ratchet disk 6, unless otherwise restrained as hereinafter set forth, and vice versa.

70 During the normal operation of the mechanism, in either direction it is required that the ratchet pawl which is not held in restraint by engagement of its cam face 15 or 15' and cam stud 16 or 16' be held in a retracted and inactive position with a view to avoid a noisy clicking in the mechanism, and to such end a guard or holding member is provided, as follows:

75 A circular guard disk 17 formed with a pair of opposed openings 18, preferably of a segmental form, is loosely mounted on the power shaft 2, and has frictional contact with the ratchet disk 6, preferably through 80 an annular ridge 19 near its outer rim engaging in a complementary annular recess in the ratchet disk 6 and held to frictional engagement by spring impelled sliding heads 20 mounted in the primary pinion 1. Said 85 guard disk 17 is operatively connected to the pinion 1 by a stud 21 on the pinion, moving in an elongated curved slot 22 in the disk 17 to admit of limited independent movement between the parts, preferably corresponding in extent with that of the heretofore independent movement between the pinion 1 and power shaft 2. Such provision for independent movement of the guard disk 17 may be between the guard disk and 90 the power shaft 2, when found most convenient.

95 The operation of the mechanism is as follows:—

100 With the parts in the position shown in Fig. 4, the power shaft 2 is moving in the contra-clockwise direction indicated by the arrow in said figure and driving the pinion 1 in the same direction. In such normal driving condition, the cam stud 16 is in engagement with the cam face 15 to hold the ratchet pawl 11 in a retracted position as shown in Fig. 2, while the companion cam stud 16' is out of engagement with the cam face 15' of its ratchet pawl 12, but with said 110 ratchet pawl 12 held in a retracted and inactive position by the engagement of an edge of the opening 18' of the guard plate 17 beneath the point of the pawl 12 as shown in Fig. 3.

115 With a stoppage of the power shaft 2, through loss of power, due to a neutral position of the reversing mechanism of the hoisting apparatus, etc., and with the load carried tending to turn the pinion 1 in a 120 125

clockwise direction as indicated by the arrow on Fig. 5, the action is as follows:—

The pinion 1 moving in a clockwise direction under the load, and in a manner independent of the guard disk 17, by travel of its stud 21 in the elongated slot 22 of said disk, carries the ratchet pawl 12 from under the guard disk 17, to a released condition and so that said pawl will move into locking engagement with the ratchet disk 6 to stop and hold the pinion 1 against further turning movement and thus prevent a runaway of the hoisting mechanism under the stress of the above mentioned load.

With the load carried tending to turn the pinion 1 in a contra-clockwise direction as indicated by the arrow in Fig. 6, the action is as follows:

The pinion 1 turning in such contra-clockwise direction, moves by means of its keyway 4, independent of the power shaft 2 and its spline 3, to carry the ratchet pawl 11 out of engagement with the cam stud 16, and permitting said pawl 11 to move into locking engagement with the ratchet disk 6 to stop and hold the pinion 1 against further movement in the described contra-clockwise direction. In such operation the stud 21 of the pinion 1 has initial independent movement in the elongated slot 22 of the guard disk 17 but in a final movement engages and moves the guard disk to the position indicated in Fig. 6, for a succeeding step in the operation of the mechanism.

With the parts in the position indicated in Fig. 7, the power shaft 2 is moving in the clockwise direction indicated by the arrow on said figure, and driving the pinion 1 in the same direction. In such normal driving condition of the parts, the cam stud 16' is in engagement with the cam face 15' to hold the ratchet pawl 12 in a retracted and inactive position, while the companion cam stud 16 is out of engagement with the cam face 15 of the ratchet pawl 11, but with said pawl held in a retracted and inactive position by the engagement of the opening 18 of the guard disk 17 beneath the point of the pawl 11. With the described position of the parts, the normal driving of the pinion 1 by the power shaft 12 continues until such accidental occurrences as above set forth in the contra-clockwise driving of the pinion 1 takes place when the safety operation of the parts takes in substantially the same way but in a reversed manner.

Having thus fully described my invention, what I claim and desire to secure by Letters Patent is:—

1. In a safety mechanism of the type described, the combination of a fixed support, a power shaft journalled in said support, a driven member mounted on said shaft, means for permitting limited independent turning movement between said shaft and

driven member, a ratchet disk carried by the fixed support, reversely arranged pawls carried by the driven member for stop engagement with said ratchet disk, cam projections on the power shaft having alternating engagement with said pawls to retract the same, and an orificed guard disk associated with the power shaft and driven member for alternating retracting engagement with said pawls.

2. In a safety mechanism of the type described, the combination of a fixed support, a power shaft journalled in said support, a driven member mounted on said shaft, means for permitting limited independent turning movement between said shaft and driven member, a ratchet disk frictionally held on said fixed support, reversely arranged pawls carried by the driven member for stop engagement with said ratchet disk, cam projections on the power shaft having alternating engagement with said pawls to retract the same, and an orificed guard disk associated with the power shaft and driven member for alternating retracting engagement with said pawls.

3. In a safety mechanism of the type described, the combination of a fixed support, a power shaft journalled in said support, a driven member mounted on said shaft, means for permitting limited independent turning movement between said shaft and driven member, a ratchet disk frictionally attached to the fixed support by a circular head fixed on said support, a companion ring attached to said head by clamping bolts, and a flat marginal extension on the ratchet disk arranged between said head and ring, reversely arranged pawls carried by the driven member for stop engagement with said ratchet disk, cam projections on the power shaft having alternating engagement with said pawls to retract the same, and an orificed guard disk associated with the power shaft and driven member for alternating retracting engagement with said pawls.

4. In a safety mechanism of the type described, the combination of a fixed support, a power shaft journalled in said support, a driven member mounted on said shaft, means for permitting limited independent turning movement between said shaft and driven member, a ratchet disk carried by the fixed support, reversely arranged pawls slidingly mounted in said driven member at opposite sides of its axis of rotation, springs for moving said pawls in one direction, cam projections on the power shaft having alternating engagement with said pawls to retract the same, an orificed guard disk associated with the power shaft and driven member for alternating retracting engagement with said pawls.

5. In a safety mechanism of the type de-

scribed, the combination of a fixed support, a power shaft journalled in said support, a driven member mounted on said shaft, means for permitting limited independent turning movement between said shaft and driven member, a ratchet disk frictionally held on said fixed support, reversely arranged pawls slidingly mounted in said driven member at opposite sides of its axis of rotation, springs for moving said pawls in one direction, cam projections on the power shaft having alternating engagement with said pawls to retract the same, and an orificed guard disk associated with the power shaft and driven member for alternating retracting engagement with said pawls.

6. In a safety mechanism of the type described, the combination of a fixed support, a power shaft journalled in said support, a driven member mounted on said shaft,

means for permitting limited independent turning movement between said shaft and driven member, a ratchet disk frictionally attached to the fixed support by a circular head fixed on said support, a companion ring attached to said head by clamping bolts and a flat marginal extension on the ratchet disk arranged between said head and ring, reversely arranged pawls slidingly mounted in said driven member at opposite sides of the axis of rotation thereof, springs for moving said pawls in one direction, cam projections on the power shaft having alternating engagement with said pawls to retract the same, and an orificed guard disk associated with the power shaft and driven member for alternately retracting engagement with said pawls.

Signed at Chicago, Illinois this 11th day of April, 1925.

EDWARD J. POWERS.
